UNITED STATES PATENT OFFICE.

HENRY JONES, OF BELTON, SOUTH CAROLINA, ASSIGNOR TO DRAPER COMPANY, OF PORTLAND, MAINE, AND HOPEDALE, MASSACHUSETTS.

WARP STOP-MOTION FOR LOOMS.

SPECIFICATION forming part of Letters Patent No. 673,818, dated May 7, 1901.

Application filed January 21, 1901. Serial No. 44,010. (No model.)

To all whom it may concern:

Be it known that I, HENRY JONES, a citizen of the United States, and a resident of Belton, county of Anderson, State of South Carolina, have invented an Improvement in Warp Stop-Motions for Looms, of which the following description, in connection with the accompanying drawing, is a specification, like characters on the drawing representing like parts.

This invention has for its object the production of novel warp-stop-motion mechanism particularly adapted for use in connection with looms for weaving, a feeler, which forms a part of the stop-motion, being vibrated by or through the movement of the lay, and the operation of the stopping means for the loom is also derived from the same source.

Various novel features of my invention will be hereinafter described, and particularly pointed out in the following claims.

The drawing in cross-section represents a sufficient portion of a loom to be understood with one embodiment of my invention applied thereto.

The lay A^3 , lay-swords A^X , one of which is herein shown, and the shipper-lever S , which is the only member of the stopping means herein shown, may be and are all of usual and well-known construction, the lower end of the shipper-lever being operatively connected with a knock-off arm k , mounted on a rock-shaft k' on a bracket K on the loom frame, said rock-shaft being shown as provided with a rocker-arm k^2 , which in the present instance of my invention has pivotally mounted upon it the dog k^3 , notched at its free end, as at k^4 , said dog being adapted to at times coöperate with and be engaged by a bunter a^X , mounted on the lay-sword. If the dog is elevated into the path of the bunter on the forward stroke of the lay, the rock-shaft k' will be turned to swing the knock-off arm in the direction of the arrow 5 to thereby release the shipper-lever from its usual holding notch.

The warp-stop-motion mechanism comprises detectors d , warp-receiving openings d' , and herein shown as also longitudinally slotted at d^2 to receive, support, and guide

bars d^X , and the detectors are herein shown as arranged in two parallel banks or series in a manner well known to those skilled in the art, the detectors being normally inoperative by warp-threads. I have herein shown a feeler f to coöperate with each bank or series of detectors, the feelers being connected by arms f' each with a rock-shaft f^X , mounted in brackets F , secured to the loom side, one being herein shown. To transmit rocking motion from one to the other rock-shaft, I have herein shown them as provided with intermeshing segmental gears f^2 . One of the rock-shafts f^X has fast upon it a rocker-arm f^3 , to which is pivotally connected a link f^4 , having at its lower end a longitudinal slot f^5 , entered by a stud or pin a^2 on a downwardly and rearwardly curved arm a' , secured to one of the lay-swords, near the fulcrum A^2 thereof. The lay-sword also has a rearwardly-extended lug a^3 , upon which is fulcrumed at a^4 a rocker-arm a^5 , pivotally connected at a^6 to the link f^4 back of the lay-sword, the opposite or forwardly-extended end of the rocker-arm a^5 projecting beneath the dog k^3 , and a spring s^X is connected at one end to the outer end of the rocker-arm and at its other end to a part of the lay-sword, as by a pin 6, the downward pull of the spring tending to lift the rear end of the rocker-arm.

The slot-and-pin connection between the link and the lay-sword permits a limited amount of lost motion between them equal to the play of the pin a^2 longitudinally in the slot f^5 , the spring s^X acting to normally lift the rear end of the arm a^5 and to elevate the link to thereby move the feelers toward the detectors as the lay beats up, the spring thus imparting the feeling movement; but it will be manifest that the spring at such time normally prevents any longitudinal movement of the link relatively to the lay-sword. As shown in the drawing, when the lay moves back the arm a' moves into dotted-line position and operates to draw down the link against the pull of the spring s^X , thereby swinging the feelers outward and away from the detectors; but the forward end of the rocker-arm a^5 will not normally be elevated sufficiently to bring the dog k^3 into the path

of the bunter a^x . As the lay comes forward the spring s^x acts to move the link f^4 upward, as has been stated, the bottom of the slot f^5 engaging the pin a^2 , and at such time the dog 5 remains in inoperative position, provided the feeling movement of the feeler is not arrested.

Should one of the detectors d be released, as by failure or breakage of its warp-thread, it will arrest the feeling movement of the 10 feeler on the beat up of the lay and the link f^4 will operate to turn the rocker-arm a^5 on its fulcrum a^4 , raising the end of the rocker-arm beneath the dog k^3 to place the latter in the path of the bunter, and as the lay comes 15 forward the bunter will engage the dog and through the devices shown will release the shipper-lever and effect the operation of the stopping means. Thus the vibration of the feeler is not only derived from the movement 20 of the lay-sword, but the actuation of the stopping means is also derived from the same source, and the connections between the feeler and lay-sword control the actuation of the stopping means.

25 When a feeler is arrested by a released detector, so that the upward or spring-impelled movement of the link f^4 is prevented, the longitudinal slot f^5 permits the necessary play of the pin or stud a^2 as the lay beats up, 30 so that the arm a^5 will be rocked and the detectors will not be crushed.

Having fully described my invention, what I claim as new, and desire to secure by Letters Patent, is—

35 1. In a loom, the lay and a lay-sword, a bunter, and a rocker-arm, both on the lay-sword, warp-stop-motion mechanism, including a feeler and a rock-shaft on which it is mounted, an actuating-link operatively connected with 40 the rock-shaft and lay-sword and pivotally attached to one end of the rocker-arm, a spring

tending to depress the other end of the rocker-arm, and stopping mechanism, including a dog controlled as to its position by the rocker-arm, arrest of the feeler acting through the 45 link and said rocker-arm to move the dog into the path of the bunter.

2. In a loom, the lay and a lay-sword, a bunter thereon, warp-stop-motion mechanism, including a feeler, a link between it and the lay-sword and having a lost-motion connection with the latter, a spring tending to elevate the link and effect feeling movement of the feeler, its opposite stroke being effected by movement of the lay-sword, and stopping 55 mechanism, including a dog controlled by the said connection, arrest of the feeler operating through said connection to move the dog into the path of the bunter.

3. In a loom, the lay and lay-sword, a bunter on the latter, operative on its forward stroke, warp-stop-motion mechanism, including a feeler, a spring-controlled rocker-arm on the lay-sword, a link connecting the latter and the feeler and pivotally connected 65 with the rocker-arm, and stopping mechanism, including a dog controlled as to its position by the rocker-arm, backward movement of the lay-sword acting through the link to swing the feeler in one direction, the arrest 70 of the opposite, or feeling movement of the feeler, acting through said link to rock the rocker-arm and move the dog into position to be engaged by the bunter on the forward stroke of the lay-sword.

In testimony whereof I have signed my name to this specification in the presence of 75 two subscribing witnesses.

HENRY JONES.
